US00D942212S

(12) **United States Design Patent** (10) Patent No.: **US D942,212 S**
Zhou (45) Date of Patent: ** Feb. 1, 2022

(54) **BOTTLE LID**

(71) Applicant: **TAIZHOU GUANGHANG E-COMMERCE CO., LTD.**, Taizhou (CN)

(72) Inventor: **Danhong Zhou**, Taizhou (CN)

(73) Assignee: **TAIZHOU GUANGHANG E-COMMERCE CO., LTD.**, Taizhou (CN)

(**) Term: **15 Years**

(21) Appl. No.: **29/808,139**

(22) Filed: **Sep. 17, 2021**

(30) **Foreign Application Priority Data**

Sep. 1, 2021 (CN) 202130575004.3

(51) **LOC (13) Cl.** **09-07**

(52) **U.S. Cl.**

USPC **D7/392.1**; D9/443; D7/396.2

(58) **Field of Classification Search**

USPC D9/435, 439, 440, 442-449, 450, 454, D9/531, 682-694, 723; D7/321, 391, D7/392, 392.1, 396.2, 507, 509-511, 523, D7/608, 900; D6/515

CPC B65D 83/205; B65D 83/206; B65D 83/40; B65D 2543/00046; A47G 19/2272

See application file for complete search history.

(57) **CLAIM**

The ornamental design for a bottle lid, as shown and described.

DESCRIPTION

FIG. 1 is a perspective view of a bottle lid showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the bottle lid where the bottle lid is in a configuration of use.

The broken lines in the drawings depict portions of the bottle lid that form no part of the claimed design.

1 Claim, 9 Drawing Sheets
